US00D699544S

(12) **United States Design Patent**
Lin

(10) **Patent No.:** **US D699,544 S**
(45) **Date of Patent:** **** Feb. 18, 2014**

(54) **LOCKING HEAD OF WIRE**

(71) Applicant: **Lintex Co., Ltd.**, Zhanghua County (TW)

(72) Inventor: **Chia-Sheng Lin**, Zhanghua County (TW)

(73) Assignee: **Lintex Co., Ltd.**, Zhanghua County (TW)

(**) Term: **14 Years**

(21) Appl. No.: **29/444,977**

(22) Filed: **Feb. 6, 2013**

(30) **Foreign Application Priority Data**

Oct. 26, 2012 (TW) 101220773

(51) **LOC (10) Cl.** **08-07**

(52) **U.S. Cl.**

USPC **D8/343**

(58) **Field of Classification Search**

USPC ..... D8/330, 331, 333, 334, 339-341, 343, D8/349, 164, 158, 229, 230, 367; 70/20, 70/30, 31, 38 A, 38 R, 51, 52, 57.1, 141, 70/233, 431

(57) **CLAIM**

The ornamental design for a locking head of wire, as shown and described.

DESCRIPTION

FIG. 1 is a perspective view of a locking head of wire showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view.

The broken lines immediately adjacent to the claimed areas represent the boundaries of the design. The broken lines environment is for illustrative purpose only. None of the broken lines form part of the claimed design.
